UNITED STATES PATENT OFFICE.

ADOLPH ROSNER, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

INTERRUPTER MECHANISM FOR IGNITION SYSTEMS.

Application filed January 28, 1922. Serial No. 532,407.

To all whom it may concern:

Be it known that I, ADOLPH ROSNER, a citizen of the United States, residing at 4 Ventura Street, Springfield, in the county of Hampden, State of Massachusetts, have invented certain new and useful Improvements in Interrupter Mechanism for Ignition Systems; and I do hereby declare the following to be a full, clear, and exact description of the invention, such as will enable others skilled in the art to which it appertains to make and use the same.

The present invention relates to ignition systems for internal combustion engines, and particularly to the interrupter mechanism thereof.

Heretofore, where more than one interrupter lever was used in an interrupter mechanism, the levers were in continual operation and alternately deflected, and were usually employed with engines having a large number of cylinders, so that the duty imposed upon the interrupter levers could be divided among the levers. Whether or not using more than one interrupter lever in prior systems, the interrupter contacts usually became pitted so that the interrupter was rendered inoperative, or but poorly operative. There was no provision made for quickly shifting to another set of contacts when one set became pitted, so that the proper operation of the system could continue. In one of my previous constructions, the interrupter mechanism had a pair of levers located on opposite sides of the interrupter cam, either one of which levers could be thrown out of operative engagement by a rotatable cam ring carrying two cams, one or the other of which could be moved into engagement with one or the other interrupter lever to hold it out of operative engagement with the interrupter cam.

In accordance with this part of my invention, the contact carrying members, preferably a pair of levers, are located at one side of the interrupter cam and have, together with the support for the interrupter mechanism, cooperative means movable to different positions to selectively hold any of the contact carrying members out of operative engagement with the interrupter cam, while another cam carrying member is in operative engagement with such cam:

Whether or not the contact carrying members be located at one side of the interrupter cam, this cooperative means is preferably an interfering member, such as a lever pivotally mounted on the support of the interrupter mechanism. In order that this lever may be retained in any one of its selected positions, means, which may be spring pressed, is used to normally lock it in such position. This locking means preferably comprises depressions, such as grooves provided in the lever, and a spring-pressed member, such as a spring-pressed ball, movable into such depression or groove. The contact carrying members or levers may have projecting portions, preferably spring portions, with which the interfering member or lever selectively engages to hold one or the other of the contact carrying levers out of operative engagement with the interrupter cam, and hence, selectively render either pair of contacts operative or inoperative, as desired.

By such structure, should the pair of contacts operating with the interrupter cam fail to give proper ignition or be pitted so as to operate poorly, the pivoted lever may be readily and quickly shifted to throw such contacts out of operation and, at the same time, throw the other pair of contacts into operation, thus making it possible to continue the operation of the engine. Moreover, the present invention is simpler in structure and more convenient to operate than my previous device.

In the accompanying drawing illustrating my invention in application, as an example, to a battery ignition type of timer-distributor arranged to be driven by a rotating part of a gas engine:

Fig. 1 is a view partly in side elevation and partly in vertical section of a timer-distributor embodying my invention; Fig. 2 is a top plan view of the same with the distributor cap removed and the interrupter cam shown in section; Fig. 3 is a view partly in side elevation and partly in section with means for throwing either interrupter lever out of operation; Fig. 4 is a section view taken on line 4-4 of Fig. 3; and Fig. 5 is a sectional view taken on line 5-5 of Fig. 3.

Referring more particularly to the draw-

ing, the invention is shown as applied to a battery ignition timer-distributor of the governor type having a casing 1 into which extends a timer shaft 2. The lower end of 5 the timer shaft carries a spiral gear 3 adapted to be driven by a similar gear connected to a rotating part of the gas engine. The upper end of the shaft 2 has a hexagonal cam 4 and an extension 5 upon which is 10 mounted a distributor rotor 6, the extension and rotor being non-rotatably connected together. Within the lower portion of the casing 1, the shaft carries a governor mechanism 7 of any suitable type for automatically 15 advancing and retarding the spark upon variation in engine speed. Above the governor mechanism is supported an interrupter housing 8 in the form of a cup slidably fitting within the upper open end of the casing 1. 20 Upon the bottom wall of this cup 8 is supported the interrupter mechanism which comprises a pair of interrupter levers 9 and 10, supported upon a pivot 11 fixed to the base of the cup 8. The interrupter levers 25 are formed of sheet metal and channel-shaped in cross-section and carry fibre striker-blocks 12 and 13 adapted to engage with the surface of the rotating cam 4. The levers 9 and 10 are normally urged toward 30 the cam 4 by springs 14 and 15 having an end of such springs fastened to such levers, and their other ends bearing against a head 16 of a binding post 17, the latter extending outwardly through the cup 8 and the casing 35 1 and being threaded to receive a button 18 adapted to fasten an end of a low tension lead to the binding post. The binding post is supported in a block 19 of insulating material fitting into a slot provided in the side 40 of the frame 1. The ends of the levers 9 and 10 carry movable contacts 20 which may be of platinum or tungsten, and on the bottom of the cup 8 is supported a block 21 by which is carried two screws 22 each carrying 45 at one of its ends a stationary contact 23 located opposite the movable contacts 20 carried by the levers 9 and 10. The screws 22 are adjustable through the block 21 to vary the spark gaps between the contacts, and a 50 lock nut 24, on each screw 22, acts to fix the adjusted position with the screw, in a known manner.

The bottom of the cup 8 also supports a condenser 25 to which is connected a terminal 26 bearing against the head 16 of the binding post 17, the other side of the condenser being grounded through a binding post 27 fastened to the cup 8 and extending through the casing 1. This binding post 60 carries a button 28 adapted to secure a grounded lead to the post.

The upper end of the casing 1 is surrounded by a distributor cap 29 which carries a set of high tension electrodes 30 to 65 which high tension leads, leading to the

spark plugs of the engine, may be connected, and a central electrode 31 to which may be connected a high tension lead from the spark coil. The central electrode 31 has a 70 slidable brush 32 pressed downwardly by a spring 33 against a distributor insert 34 carried by the rotor 6. The end of the insert 34 is tapered, and, during its rotation, successively supplies high tension current to the electrodes 30. 75

Opposite the ends of the interrupter levers 9 and 10 is pivotally supported in the side wall of the casing 1 a lever 35 secured to a short shaft 36 by a cross pin 37. The shaft 36 has a bearing supported 80 in a block 38 which fits into an opening 39 formed in the side of the casing 1. The shaft 36 extends inwardly through an aperture formed in the side wall of the cup 8 and has fixed to it a cross head 40 carrying pins 41 and 42 made from insulating material or fibre and located at the opposite ends of the head 40. The shaft 36 also has a pair of adjacently located longitudinal depressions or grooves 43 and 44 with a sharp 85 ridge 45 therebetween. In the head 40 is provided a recess 46 in which is located a spring 47 bearing against a ball 48 constantly urged into one of the grooves 43 and 44, depending upon the angular position of 90 the shaft 36 and the lever 35 with respect to recess 46. 95

It will be apparent from the illustrations of Figs. 3 and 5 of the drawing, that when the lever is shifted from one position to the other, the ridge 45 will pass beneath the ball 48, raising it and compressing the spring 47 until the other groove takes the position opposite the ball 48. The spring 47 will then act to press the ball 48 into this other groove, and owing to the pressure of the ball in such groove, the lever will be normally held in locked position, such pressure being sufficient to prevent the accidental throwing of the lever out of position, but of insufficient pressure to prevent a manual shift of the lever. The cross head 40 is located near the ends of the trip levers 9 and 10, and the pins 41 and 42 so located as to move against and engage with extensions 49 and 50, fastened to the ends of the interrupter levers 9 and 10, respectively. 110

These extensions are of spring metal and somewhat resilient. The extensions 49 and 50 extend beyond the ends of the levers 9 and 10 and in the paths of the pins 41 and 42, so that when the lever 35 is shifted in one position, the pin 41 will press against the extension 49 and move it from the position shown in full lines to that shown in dotted lines in Fig. 4 of the drawing, and when the lever 35 is shifted to its other position, the pin 41 will engage with and move the extension 50 from the position shown in dotted lines to that shown in full 115 120 125

lines in Fig. 4 of the drawing. In this way either interrupter lever 9 or 10 is moved, so that its striker block is no longer engaged by the cam 4, and also the pair of contacts 20 and 23 of such lever are separated a greater distance than the usual spark gap distance. At the same time the other interrupter lever is in operative engagement with the cam and not then affected by the shifting means shown in Figs. 3, 4 and 5 of the drawing.

Having thus described my invention what I claim is:

1. An interrupter for ignition systems comprising a cam, a support for the interrupter mechanism, contact carrying members on said support at one side of said cam and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam.
2. An interrupter for ignition systems comprising a cam, a support for the interrupter mechanism, contact carrying members on said support at one side of said cam and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam, and means to normally lock said movable means in selected position.
3. An interrupter for ignition systems comprising a cam, a support for the interrupter mechanism, contact carrying members on said support and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam, said lever being provided with depressions, a spring-pressed member movable into any of said depressions to normally lock said lever in any selected position.
4. An interrupter for ignition systems comprising a cam, a support for the interrupter mechanism, contact carrying members on said support and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam; said movable means comprising a lever pivotally mounted on said support and movable into any of said different positions.
5. An interrupter for ignition systems comprising a cam, a support for the interrupter mechanism, contact carrying members on said support and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam; said movable means comprising a lever pivotally mounted on said support and movable into any of said different positions, said lever having means to normally lock said lever in selected position.
6. An interrupter for ignition systems comprising a cam, a support for the interrupter mechanism, contact carrying members on said support and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam, said movable means comprising a lever pivotally mounted on said support and movable into any of said different positions, said lever being provided with depressions, a spring-pressed member movable into any of said depressions to normally lock said lever in any selected position.
7. An interrupter for ignition systems comprising a cam, a support for the interrupter mechanism, contact carrying members on said support and movable by said cam, springs operable to normally hold said

contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam, said movable means comprising a lever pivotally mounted on said support and movable into any of said different positions, said lever being provided with grooves, a spring-pressed ball movable into any of said grooves to normally lock said lever in any selected position.

8. An interrupter for ignition systems comprising a cam, a support for the interrupter mechanism, contact carrying members on said support and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam, said movable means having cooperative means normally locking said movable means in any selected position.

9. An interrupter for ignition systems comprising a cam, a support for the interrupter mechanism, contact carrying members on said support and movable by said cam, springs operable to normally hold said contact carrying members against said cam, sets of relatively movable contacts carried by said support and said contact carrying members, said contact carrying members and said support having cooperative means movable to different positions for selectively holding any of said contact carrying members out of operative engagement with said cam, while another of said contact carrying members is in operative engagement with said cam, said movable means having cooperative grooves and a spring-pressed ball normally locking said movable means in any selected position.

55 10. An interrupter for ignition systems comprising a cam, a support for the interrupter mechanism, interrupter levers on said support and movable by said cam, pairs of relatively movable contacts carried by said support and said levers, said levers and said support having cooperative means movable to different positions for selectively rendering any of said pairs of contacts operable, while rendering the other pairs of said contacts inoperable.

11. An interrupter for ignition systems comprising a cam, a support for the interrupter mechanism, contact carrying members on said support at one side of said cam, and movable by said cam, springs operable to normally hold said contact carrying members against said cam, pairs of relatively movable contacts carried by said support and said contact carrying members, an interfering member on said support and movable to different positions for selectively rendering any of said pairs of contacts operable, while rendering the other pairs of said contacts inoperable. 70 75

12. An interrupter for ignition systems 80 comprising a cam, a support for the interrupter mechanism, contact carrying members on said support and movable by said cam, springs operable to normally hold said contact carrying members against said cam, 85 pairs of relatively movable contacts carried by said support and said contact carrying members, said contact carrying members being provided with projecting portions, an interfering member on said support and 90 movable to different positions to selectively engage with said projections for rendering any of said pairs of contacts operable, while rendering the other pairs of said contacts inoperative. 95

13. An interrupter for ignition systems, comprising a cam, a support for the interrupter mechanism, contact carrying members on said support and movable by said cam, springs operable to normally hold said contact carrying members against said cam, sets of relatively movable contacts carried by said support and said contact carrying members, said contact carrying members being provided with spring projecting portions, and an interfering member on said support and movable to different positions to selectively engage with said spring portions to render any of said pairs of contacts operable, while rendering the other pairs of said contacts inoperable. 100 105 110

14. In a distributor having a casing, a pair of alternative switch arms within said casing, and means for selectively adjusting said arms into or out of positions of use 115 from the exterior of said casing.

15. In a distributor, a cam shaft, alternative ignition switch elements engageable with said cam shaft, and a common means for establishing one of said elements in operative engagement with said shaft and disengaging the other element therefrom. 120

16. In a distributor having a casing, a pair of alternative switch arms within said casing for controlling the ignition circuit, a 125 rock shaft mounted in the wall of said casing, a handle carried by said shaft exteriorly of said casing and a head carried by said rock shaft within the casing engageable selectively with said switch arms to 130

raise either of the same from operative position of disuse, said means having limiting positions in which the respective switch

17. A distributor comprising a pair of switch arms for alternatively controlling the ignition circuit, springs urging said arms to their circuit controlling positions, a common means for shifting either arm to a position of disuse, said means having limiting positions in which the respective switch arms are acted upon, and a spring detent for 10 maintaining said limiting positions.

In testimony whereof I affix my signature.

ADOLPH ROSNER.
